UNITED STATES PATENT OFFICE.

EDWIN HARDING, OF ALEXANDRIA, LOUISIANA.

ICE-SAWING DEVICE.

Application filed November 30, 1921. Serial No. 518,595.

To all whom it may concern:

- Be it known that I, EDWIN HARDING, a citizen of the United States, residing at Alexandria, in the Parish of Rapides and 5 State of Louisiana, have invented certain new and useful Improvements in Ice-Sawing Devices, of which the following is a specification, reference being had to the accompanying drawings.
- 10 This invention relates to sawing devices, particularly to those designed primarily for cutting blocks of ice, and has for its object the provision of a novel power driven circular saw device for cutting blocks of ice into small pieces of any desired dimensions for 15 the retail trade whereby the pieces cut will be perfectly even and smooth so as not only to have the proper weight but also to be attractive to the consumer.
- 20 An important object is the provision of a device of this character including a rigid supporting frame and a swinging frame carrying a circular saw, lever operated means being provided for moving the swinging frame to move the saw with respect to the ice, the saw being driven by a directly associated electric motor which is readily controllable by the operator to effect starting and stopping.
- 25 Another object is the provision of a device of this character in which the drive motor is mounted in a peculiar manner and is movable so as to effect tightening of the drive belt.
- 30 Yet another object is the provision of a device of this character which is provided with bumper means for limiting the movement of the swinging frame in one direction and which is also equipped with means for 35 limiting movement in the other direction, in conjunction with shock absorbing or cushioning mechanism which will operate to make the action smooth.
- 40 A still further object is the provision of an ice guide structure with which is associated a gauge which is adjustable for varying the size of the pieces cut so that they 45 will have the desired weight.
- 45 An additional object is the provision of a device of this character which will be simple and inexpensive in manufacture and installation, a great time and labor saver, efficient and durable in service and a general improvement in the art.
- 50 With the above and other objects and ad-

vantages in view, the invention consists in the details of construction to be hereinafter more fully described and claimed, and illustrated in the accompanying drawings, in which:—

60 Figure 1 is a front elevation of the device;

Figure 2 is a side elevation;

Figure 3 is a cross sectional view through the device taken above the shock absorbing means;

Figure 4 is a plan view showing the ice guide structure;

Figure 5 is a vertical sectional view showing the construction of the ice guide; and

70 Figure 6 is a sectional view through the ice gauge.

Referring more particularly to the drawings, the letter A designates a suitable base which may be the floor of an ice house or 75 which might be a platform or the like secured thereto, and at some point this base is formed with an opening or recess B for a purpose to be described. The most advantageous place in which the device may be used 80 is near the delivery chute of an ice vault so that the ice may be cut and delivered by the one attendant having charge, thereby avoiding any necessity for the employment of additional help. It is, of course, though to be 85 understood that the device is equally capable of use at any place where ice is to be cut.

In carrying out the construction of the device I provide a rigid frame which includes uprights 10 which in actual practice may be 90 formed as sections of pipe of suitable size. At their lower ends these uprights 10 are provided with supporting feet 11 which are suitably bolted on to the floor or platform, and at their upper ends the uprights carry 95 castings 12 which are connected by a cross bar 13 which may also be formed as a pipe section. Secured to the castings 12 are inclined brace members 14 which have their lower ends provided with bearing feet 15 100 which are secured to the floor or platform rearwardly of the feet 11.

The device further includes a movable frame which includes a plate 16 having a bearing 17 rotatably engaged upon the cross 105 bar 13 and prevented from longitudinal movement therealong by stop collars 18. Secured to the lower end of the plate is a bar or pipe section 19 which has its lower end carrying a yoke 20 having its arms pro- 110

vided with bearings 21 for a shaft 22 which has one end carrying a pulley 23 and its other end carrying a circular saw 24 of suitable diameter, held in place by the usual 5 clamping structure illustrated at 25. The saw 24 operates within the opening or recess B in the floor or platform.

Slidably adjustably mounted upon the plate 16 is an electric motor 26 of the moisture proof type and this motor has its shaft carrying a pulley 27 about which is trained a belt 28 which is in turn trained about the pulley 23 for driving the saw 24. Threaded through an extension 29 on the plate 16 is a 15 set screw 30 which engages the base of the motor whereby to effect adjustment of the motor with respect to the plate 16 so that tightening of the belt 28 may be effected.

Secured upon the floor or platform is a 20 bracket 31 upon which is pivoted, as shown at 32, an operating lever 33 with which is pivotally connected a link 34 which extends rearwardly and which is pivotally connected at 35 with the upper end of an arm 36 secured upon one end of a rock shaft 37 journaled in suitable bearings 38 on the floor or platform. The other end of the shaft 37 carries an arm 39 with which is pivotally connected a link 40 which is in turn pivotally 25 connected with a suitable ear on the rear side of the yoke 20. By swinging the lever 33 in one direction or the other it will be apparent that the swinging frame carrying the saw will be correspondingly moved upon 30 the cross bar 13 as a pivot.

Any suitable switch device, not shown, 35 may be provided for controlling the electric motor. The details of construction of such a control switch form no part of the present invention and are therefore not illustrated.

It is preferable to provide a trough or channel shaped guard 42 which extends over the saw 24 and which is carried by arms 43 which have their ends secured between ears which have their ends secured between 45 clamping members 44 engaged formed on clamping members 44 upon the support 19. I also provide an arm 45 which is secured between these clamping members and which is engageable with a bar 46 extending transversely between the brace 50 elements 14, the purpose of this bumper structure being to limit the rearward swinging movement of the movable frame. I also provide a flexible member, such as a chain 47 which has one end connected with the bar 46, as indicated at 48, and which has its 55 other end connected with one of the clamping members 44, as indicated at 49, the purpose of this chain being to limit movement of the swinging frame forwardly.

60 I also provide a shock absorber structure which is pivoted, as indicated at 50, on the top of the bar 46 and which includes a cylinder 51 within which operates a piston 52 carried by a piston rod 53 which is pivotally connected at 54 with the support 19.

The cylinder is provided at one end with any suitable relief valve or hole 55 for permitting the outlet and inlet of air.

I also provide the floor A with an ice guide which comprises upright plate members 56 between which the saw 24 is designed to pass and these plate members are suitably secured by any preferred means. I also provide a similar upright plate member 57 which terminates at one side of the pit or recess B. It is designed that the blocks of ice to be cut should be slid along the floor between the plate 57 and the adjacent plate 56 and it is preferable that these two plates have flaring ends 58 whereby to facilitate the entrance of the block therebetween.

While it is not essential, yet I prefer to employ a gauge which is mounted upon the floor A at the end of the plate 56 most remote from the entrance of the guideway, 85 and this gauge includes an upright bracket 59 secured upon the floor as by bolts or the like, and having associated therewith a right angularly shaped plate member 60 which carries two bolts 61 freely movable through 90 suitable holes in the bracket 59 and carrying clamping nuts 62 which are engaged against opposite faces of the bracket. By properly adjusting the nuts 62 it will be apparent that the plate member 60 may be disposed 95 at different distances from the bracket for constituting a stop against which is engaged the end of a block of ice to be cut, and the adjustability of the gauge permits variation 100 in the length of the pieces cut.

In the use of the device the block of ice to be cut is pulled or pushed along the floor or platform into the guideway and is engaged against the gauge. The block will then be disposed in the path of travel of the saw 105 when the movable frame is swung. Assuming that the saw is rotating, the operator grasps the lever 33 and pulls it forwardly whereupon the swinging frame will be moved forwardly owing to the link and lever connections described and shown, to bring the saw into engagement with the block of ice and this will naturally result in cutting the ice. In this way it will be seen that the 110 block may be cut into any number of pieces of desired size, the pieces being smoothly and uniformly cut so as to avoid waste and present the cut pieces in a manner attractive to the customer. The size of the pieces may 115 be varied by adjusting the gauge. It is to be noted that there is no chipping or waste such as is occasioned by the use of the ordinary ice picks and that the pieces may be cut accurately so that they will have the desired weight.

When the swinging frame is moved forwardly, as above described, to effect the cutting action it is apparent that the piston 52 operating within the cylinder 51 will prevent the saw from being brought too quickly 130

into engagement with the block of ice and this will prevent injury to the saw. The forward movement of the frame is limited by the action of the chain 47, while the rearward movement is limited by the engagement of the bumper arm 45 with the bumper bar 46. The guard 42 is simply a safety device for preventing ice from falling on to the saw and also tending to prevent the operator from coming in contact with the saw during use of the device.

From the foregoing description and a study of the drawings it will be manifest that this machine will work a great saving in time and labor and that it should recommend itself for use where quick and accurate service is a desirable quality. Owing to the simplicity of the construction and the fewness of the parts it is apparent that there is nothing to get out of order and owing to the substantial construction it is apparent that the device should possess great durability and satisfactorily perform all the functions for which it is intended.

25 While I have shown and described the

preferred embodiment of the invention it is of course to be readily understood that I reserve the right to make such changes in the form, construction and arrangement of parts as will not depart from the spirit of the invention or the scope of the subjoined claim.

Having thus described my invention, I claim:

An ice cutting device comprising an upstanding stationary frame, a swinging frame 35 pivotally mounted at the top of the stationary frame, a shaft journaled in said swinging frame, a circular saw carried by said shaft, means for driving said shaft, means for moving said swinging frame, and a 40 cushioning device for controlling the speed of movement of the swinging frame comprising a cylinder pivotally connected with the stationary frame and a piston operating therein and pivotally connected with the 45 swinging frame.

In testimony whereof I hereunto affix my signature.

EDWIN HARDING.
